UNITED STATES PATENT OFFICE.

JOSEPH W. KAOUGH, OF DALLAS, TEXAS, ASSIGNOR TO THE GUIBERSON CORPORATION, OF DALLAS, TEXAS, A CORPORATION OF DELAWARE.

WRENCH.

Application filed November 8, 1923. Serial No. 673,609.

To all whom it may concern:

Be it known that I, JOSEPH W. KAOUGH, citizen of the United States of America, residing at Dallas, in the county of Dallas 5 and State of Texas, have invented certain new and useful Improvements in Wrenches, of which the following is a specification.

This invention relates to new and useful improvements in wrenches.

10 The invention has particularly to do with that type of wrench which is designed for use on pipes, well casing and tool joints, or other cylindrical objects which are used in a perpendicular position.

15 A particular object of the invention is to provide a pair of clamping jaws each having closing fingers, whereby the jaws are closed in unison and a wide range of pipe sizes may be handled in an expeditious manner.

20 Another object is to provide means for intermeshing the free ends of the clamping jaws, whereby they are prevented from sagging, together with a self-latching device for fastening said ends of the jaws together.

25 A further object is to provide the faces of the gripping and clamping jaws with concavities, whereby pipes of comparatively small diameters as well as pipes of larger 30 diameters may be engaged without adding slips or shoes to the jaws.

An important advantage of this invention is that much smaller pipe sizes may be engaged than that with a single clamping 35 jaw such as is shown in my co-pending application filed of even date herewith.

40 A construction designed to carry out the invention will be hereinafter described together with other features of the invention.

45 The invention will be more readily understood from a reading of the following specification and by reference to the accompanying drawings, in which an example of the invention is shown, and wherein:

Fig. 1 is a plan view of a wrench constructed in accordance with my invention,

Fig. 2 is a side elevation of the same,

Fig. 3 is an enlarged view of the head and jaws,

Fig. 4 is a detail of a modified form of jaw mounting,

Fig. 5 is a sectional view on the line 5—5 of Fig. 4,

Fig. 6 is another modification of the jaw mounting, and

Fig. 7 is an end view of the same.

In the drawings the numeral 10 designates a head having cheek plates 11 connected at one side by a web 12 and at the other side by a web 13, thus providing a space between the plates extending longitudinally through the head. The head has a concaved seat 14 at its forward portion. A lug 15 is formed on the extreme left hand end of the head, while inwardly offset ears 16 are provided on the extreme right hand end of the head.

A gripping jaw 17 has a reduced ear 18 fitting between the ears 16 as is shown in Fig. 2. A bolt 19 passing through the ears 16 and 18 acts as a pivot for the jaw. The jaw swings through the seat 14. The jaw has dies 20 and a comparatively deep concavity 17' in its gripping face located between said dies. This permits the jaw to engage and grip pipes of various diameters, the term pipe being used generically for any cylindrical article.

A pair of clamping jaws 21 and 22, respectively, are mounted on the head. The jaw 21 has ears 23 counter-sunk in the ears 16 and mounted on the bolt 19, so as to be substantially flush with the cheek plates. The jaw 22 has ears 24 engaging on the bolt 19' passing through the lug 15. The free end of the jaw 22 has a converging socket 25 which receives the reduced and beveled end 26 of the jaw 21 at the center of the wrench, whereby sagging of the jaws is prevented. The jaw 21 has a hook latch 26' on its reduced end which engages in a keeper 27. The keeper is pivoted on the free end of the jaw 22. A yoke spring 28 has one end straddling the latching-end of the keeper and its inner end embracing the jaw 22, while the sides of the spring are coiled about the pivot of the keeper. The ends of the hook and keeper are sufficiently rounded to cause an easy self-latching action when the clamping jaws are swung together.

The jaws 21 and 22 have dies 21' and 22' respectively, and each has a concavity 21' extending to its free end. These concavities register when the jaws are closed and form a continuous arc. In each concavity is a die 22'. This structure permits the jaws to firmly grip various diameters of pipe.

An important feature of the invention resides in jaw closing fingers 29 formed on

the pivoted ends of the clamping jaws and arranged in pairs so as to straddle the cheek plates when said jaws are closed. When the jaws are opened the fingers are swung 5 into the path of the pipe.

The gripping jaw 17 has an inner curved face 39 in position to be engaged by a displacing member 40 on the inner end of a handle 42 mounted on a pin 41 secured in 10 the head. The member 40 is sufficiently broad to displace the jaw 17 from the seat 14 and into gripping position when the handle is swung. While I have shown the handle and the member 40, it is to be understood 15 that any means may be used for displacing the jaw 17.

It is desirable to hold the handle 42 against swinging and the head in central position and while any suitable means may 20 be used for this purpose, I have found a spring latch bolt to give satisfactory results. On the handle is mounted a housing 44 in which a pair of headed bolts 45 are mounted to slide.

25 The cheek plate on this side has a stud 46 on its inner end relatively between the bolts. Each bolt has a coiled compression spring 47 confined thereon and bearing against the housing and tending to withdraw the bolts from the path of the stud.

An abutment plate 48 is fastened on the handle 42. Each bolt 45 has a hand hook 49 and by grasping either of these, the bolt thereof may be displaced against the tension of its spring 47 and caught against the edge of the plate 48, whereby the head of the bolt will be held in the path of the stud. By displacing both bolts the head 10 and the handle will be engaged for unitary 30 movement.

When only one of the bolts is displaced the handle is free to swing independently in one direction only. As is shown in Fig. 1, the right hand bolt 45 is displaced and when the handle is swung to 35

the left the head will also be swung therewith, but when the handle is swung to the right the head 10 will remain (relatively) stationary and the member 41 will fulcrum on its pin 41, forcing the jaw 17 into action.

40 In Figs. 4 and 5 I have shown a modified form in which the jaw 17 is shown with a lug 50 extending outwardly of ears 16' formed on the head. The jaw 17 has a slot 17' in which a bushing 51 is confined on a pin 19' which latter projects beyond the ends of the bushing and has its ends confined in the ears 16' as is shown in Fig. 5.

One end of the pin is fastened by a set screw 52. The ends of the pin being flush with the outer faces of the plates 11, allow the fingers 29 of the clamping jaw 21 to swing thereover. The jaw 21 is pivoted on the end of the lug 50 by a bolt 53. This arrangement permits the jaws to undergo a 45 rotary movement circumferentially of the

pipe in gripping the same and also increases the amplitude of the swing of the gripping jaw.

In Figs. 6 and 7 another modification is shown in which the head has a lug 60 extending from its right hand end and which receives the forked end of the jaw 21. The gripping jaw 17 is pivoted on a pin 61 having its ends confined in the cheek plates 11. This pin is held by a set screw 62 in one of the plates. The fingers 29 of the jaw 21 swing over the plates and the ends of the pin 61, and said jaw 21 is pivoted on a bolt 63 mounted in the lug 60. This form has the advantage of two bearing points for the 50 fulcrums of the jaws and also offers more metal for the parts at these points.

In using the wrench the clamping jaws 21 and 22 are swung open as is shown in the dotted lines in Fig. 3. The head 10 is 55 moved toward the pipe which is engaged by the fingers 29 which latter were swung into its path when the jaws were opened. As the movement of the head toward the pipe is continued the fingers are displaced, 60 whereby the jaws 21 and 22 are swung in behind the pipe until the hook 26 engages in the keeper 27 and the clamping jaws are thus fastened as is shown in full lines in Fig. 3 and in full lines in Fig. 1. 95

The bolts 45 are both engaged with the lug 46 during the jaw-closing movement, but in order to swing the member 40 and displace the jaw 17 to grip the pipe, one of the bolts 45 must be retracted, according to 100 the direction in which it is necessary to swing the handle 42. When the handle is released it may be swung and the pipe firmly gripped.

It is obvious that other latching means 105 could be used and various other changes, modifications and alterations may be made within the scope of the appended claims.

What I claim, is:

1. In a wrench, the combination of a head 110 having a seat, an arcuate gripping jaw swinging through the seat, means including a handle for displacing the gripping jaw into gripping position, a pair of self latching clamping jaws pivoted on the head, and 115 jaw closing fingers carried by the clamping jaws.

2. In a wrench, the combination of a head having a seat, an arcuate gripping jaw swinging through the seat, means including 120 a handle for displacing the gripping jaw into gripping position, a pair of clamping jaws pivoted on the ends of the head, means for latching the free ends of the clamping jaws, and jaw closing fingers carried by the 125 clamping jaws.

3. In a wrench, the combination of a head having a seat, an arcuate gripping jaw swinging through the seat, means including 130 a handle for displacing the gripping jaw

into gripping position, a pair of clamping jaws pivoted on the ends of the head, a hook latch on the free end of one of the clamping jaws, a self-latching keeper on the free end of the other clamping jaw engaged by the hook when the jaws are closed, and jaw closing fingers carried by the clamping jaws.

4. In a wrench, the combination of a head having a seat, an arcuate gripping jaw 10 swinging through the seat, means including a handle for displacing the gripping jaw into gripping position, a pair of clamping jaws pivoted on the ends of the head, a hook latch on the free end of one of the clamping 15 jaws, a self-latching keeper on the free end of the other clamping jaw engaged by the hook when the jaws are closed, jaw closing fingers carried by the clamping jaws, and a socket on the free end of one of the clamping 20 jaws receiving the end of the other clamping jaw.

5. In a wrench, the combination of a head having a seat, an arcuate gripping jaw pivoted in the head and having a concavity

in its face and dies at each end of the concavity, means in the head for actuating the gripping jaw, a pair of clamping jaws pivoted on the ends of the head and having pipe receiving concavities in their faces, means for fastening the free ends of the 30 clamping jaws together, and jaw closing fingers carried by the pivoted ends of the clamping jaws.

6. In a wrench, the combination of a head having a seat, an arcuate gripping jaw 35 pivoted in the head and having a concavity in its face and dies at each end of the concavity, means in the head for actuating the gripping jaw, a pair of clamping jaws pivoted on the ends of the head and having 40 pipe receiving concavities in their faces, dies in the concavities of the clamping jaws, means for fastening the free ends of the clamping jaws together, and jaw closing fingers carried by the pivoted ends of the 45 clamping jaws.

In testimony whereof I affix my signature.
JOSEPH W. KAOUGH.
